UNITED STATES PATENT OFFICE.

WILLIAM BIRDSALL, OF EAST ORANGE, NEW JERSEY.

COMBINED COLLAR-FASTENER AND NECKTIE-GUIDING DEVICE.

1,076,622.

Specification of Letters Patent. Patented Oct. 21, 1913.

Application filed March 17, 1913. Serial No. 784,887.

To all whom it may concern:

Be it known that I, WILLIAM BIRDSALL, a citizen of the United States, and a resident of East Orange, county of Essex, and 5 State of New Jersey, have invented certain new and useful Improvements in Combined Collar-Fasteners and Necktie-Guiding Devices, of which the following is declared to be a full, clear, and exact description.

10 This invention relates to improvements in combined collar fasteners and necktie guiding devices, and has for its primary object the provision of an article of this kind of simple, cheap, and improved construction, capable of performing the functions of detachably securing a collar to the neckband of a shirt, and supporting and guiding the necktie at the back of the collar in such manner as to eliminate any tendency 15 for it to bind, or become wedged in the fold of the collar, or to fall below the same.

Another object is to provide an article of 20 this class, having collar attaching means associated with an upright tie guiding member, arranged to spread apart the inner and outer members of a turn-down collar, and closed at the top and bottom, but provided with a gap in one of its sides, whereby the tie may be readily inserted or removed from it.

25 The present invention is in the nature of an improvement upon the invention disclosed in my former application for patent on combined collar fasteners and necktie guiding devices filed by me in the United States Patent Office on the 12th day of February, 1913, and given the Serial Number 747,905. In my continued experiments with the various forms of the invention therein illustrated and described, I have discovered 30 that these forms would be improved upon if the guiding device and collar fastener were constructed of a single piece of stiff material, for instance metal, and if the top and bottom of the tie guiding loop were 35 permanently closed, a gap being provided on one side of the loop, through which the tie could be readily inserted or removed. Moreover, the advantage of having a flat, wide, neck portion for engaging the edges 40 of the rear button-hole of a collar is readily apparent, inasmuch as such construction tends to hold the tie guiding loop in an upright position, and in designing the form illustrating the embodiment of the present 45 invention, I have employed a flat strip or blank folded in a peculiar manner, so as to

provide an article having many additional advantages over my prior forms; its construction is clearly set forth in the following specification.

60 The invention is illustrated in the accompanying drawing in which—

Figure 1, is a perspective view of a turn-down collar (partly broken out) and necktie, showing the preferred form of the present invention applied thereto; Fig. 2, is a perspective view of a fragment of the collar and tie with the combined collar fastener and guide secured in place on the collar; Fig. 3, is a rear perspective view of a fragment of a shirt and its neckband with the device secured thereon, the collar being omitted from this view; Fig. 4, is a vertical, cross section through the collar, tie and neckband, showing the device in position 70 for attaching the collar to the neckband, and for guiding the tie in the fold of the collar, and Fig. 5, is a face view of a blank from which one of the devices may be constructed.

80 In said views, A, designates a turn-down collar of ordinary construction, B, a necktie held in the fold of the collar, and C, the neckband of a shirt c, (only fragments of the neckband and shirt are illustrated, but 85 their construction is well known).

The combined collar fastener and tie guide is seen at D, and as shown, in the preferred embodiment of the invention, consists of a single piece of material, (preferably metal, although not necessarily so) which, when folded in accordance with the hereinafter described manner, is given the shape clearly shown in Figs. 1 to 4 inclusive.

90 Referring now to the finished article, it will be seen that it comprises an upright tie guiding loop 10, arranged to stand in the fold of a collar—that is between the band a, thereof, and its outer portion or fold a'. Said tie guiding loop 10, is formed with a 100 gap 11, at one side, through which the tie may be readily inserted into the loop, or removed therefrom, and as here shown, said gap is left between two tongues 12, 13, that are bent toward each other from the top and 105 bottom of the upright bar 14, of the tie guiding loop. The bends at the junctures between the tongues 12, 13, and bar 14, are substantially U shaped in form, and sufficient space is maintained between the bar 110 and tongues to admit a tie, and allow it to play freely back and forth therein when its

ends are drawn in one direction or another. The height of the tie guiding loop should be approximately equal to the width of a necktie at its middle portion, so as to obtain the best results, but slight variations in the height of the loop are immaterial so far as the operation of the device is concerned. When the loop, or tie guiding member of the device is in place in the fold of a turn-down collar, it maintains the inner and outer collar members in spread condition at the back, thus facilitating the free movement of the tie in the fold of the collar.

Projecting from the side of the bar 14, 15 of the loop 10, is a short neck 15, which is adapted to extend through the rear button-hole a^2 of the collar, (see Figs. 2 and 4) said neck terminating in a U shaped collar fastening device, or hook 16, which is arranged 20 to be hooked under the free lower edge of the neckband C; the neckband of the ordinary shirt being formed with a flap c^1 , at the back, having a free lower edge and provided with a collar button-hole c^2 , but with 25 the present form of the invention, it is preferred to pass the tang 17, of the hook 16, under the lower free edge of the flap c^1 , bringing the lower bend of the hook 16, against its lower edge. I find that this arrangement of collar fastening means, not only is simple, but it is easily applied to the neckband, and perfectly holds the collar in place thereon at the back.

In constructing the form of the invention 35 shown, a blank, which may comprise a strip of stiff material d , preferably metal, (see Fig. 5) is first folded upon itself along the dotted line d^1 , the section X, being folded down on the section Y. The two parts 13, 40 of the folded piece are then folded up and back over the part 14, along the dotted lines d^2 , (which lines are now co-incident with each other) thus forming the U shaped bend at the bottom of the loop member 10; the 45 part 14, constituting the bar of the tie guiding loop, and the parts 13, constituting the lower tongue. The end of the blank indicated by 12, is then folded over the part 14, on the dotted line d^6 , to form the inverted U 50 bend and tongue at the top of the loop 10, thus completing the tie guiding portion of the device. The section 19, of the blank lying under and contiguous with the bar portion 14, is then folded down and back 55 along the dotted line d^8 , to form the U bend or neck 15, and tang 18, of the hook 16; and the end 17, of the blank is then folded down and along the dotted line d^{10} , to form the U bend at the bottom of the hook 16, and 60 tang 17, thereof. Obviously, the exact manner of folding up the blank, as above set forth, is not essential in the construction of the device, but it enables the article to be made economically, and of a solid and 65 substantial construction.

In use, the terminal end of the tang 17, is thrust through the rear button-hole of a collar from the inside of the fold, then is pushed upward until the U bend at its bottom passes through the button-hole, and thereafter the device is pushed downward until the inverted U bend or neck 15, extends through the button-hole, thus leaving the entire collar attaching hook on the outer face of the band a , of the collar. The device having been fastened in place upon the collar, the necktie may be inserted through the gap in the tie guiding loop and laid in the fold of the collar. This position of the parts is best seen in Fig. 2. To 70 secure the back of the collar to the shirt, the tang 17, of the collar attaching hook is slipped under the lower loose edge of the neckband. The collar having been buttoned in front, the tie may be freely drawn back and forth in the fold thereof, the tie guiding loop, supporting and guiding the middle portion of the tie at the back of the collar and preventing it from working up and becoming wedged in the crease of the collar, 75 or from falling below its proper position.

By reason of the flat, wide neck 15, and its engagement with the straight button-hole of the collar, any tendency for the tie guiding loop to tilt when the tie is drawn there-through is practically eliminated, but the loop remains upright and guides the tie 80 perfectly at the back of the collar.

It is quite possible to construct the tie guiding loop and collar attaching means of 85 separate pieces suitably secured together, and I am aware that other slight changes in the exact form of construction are possible without departing from the spirit of 90 this invention; I do not, therefore, desire to limit myself to the exact construction 95 shown and described except as may be necessitated by the prior state of the art and by the scope of the appended claims.

I claim as new and desire to secure by Letters Patent:

1. As a new article of manufacture, a combined collar fastener and necktie guiding device, comprising a single strip of stiff material folded upon itself near one end to 100 form a down-turned tongue, and between its ends doubled upon itself, and the doubled portion folded upon itself to form an up-turned tongue extending toward the first named tongue, said tongues having a gap 105 between their terminal ends; the remainder of the strip being folded down and up to 110 form an inverted U shaped neck portion, and a U shaped hook portion, for engagement with a neckband of a shirt.

2. As a new article of manufacture, a combined collar fastener and necktie guiding device, comprising a single piece of metal, consisting of an upright portion having 115 an inverted U bend at its top, and a 120

companion **U** bend at its bottom, forming an open sided tie receiving loop, the strip being doubled back upon itself along the outer sides of the lower **U** bend, and folded down and up to form an inverted **U** bend near the middle of the upright portion, and a **U** bend near the bottom of the **U** bend

at the bottom of the upright portion; substantially as and for the purpose specified.

WILLIAM BIRDSALL
